JOSHUA TEDFORD, OF CHICAGO, ILLINOIS.

PRESSING MACHINE.

Application filed March 18, 1924. Serial No. 700,079.

To all whom it may concern:

Be it known that I, JOSHUA TEDFORD, a citizen of the United States, and resident of Chicago, in the county of Cook and State of Illinois, have invented certain new and useful Improvements in Pressing Machines, of which the following is a specification.

My invention relates to improvements in pressing machines, and it consists in the combinations, constructions and arrangements herein described and claimed.

An object of the invention is to obviate the wrinkling, kinking and constriction of tapering trousers legs near the lower ends thereof when the trousers legs are pressed.

To this end, the invention contemplates the provision in pressing machines of generally ordinary construction of means affording facilities for stretching the tapering lower end portions of trousers legs at the time the trousers legs are pressed, the stretched portions of the trousers legs being uniform in width and extending from the lower ends of the legs a distance sufficient to preclude wrinkling, kinking or constriction of the lower end portion of the trousers legs.

A further object of the invention is to provide a device of the character described which is particularly well adapted for use in the pressing of tapering trousers legs having the lower end portions thereof turned back to provide cuffs, the attachment being adapted to effect stretching of the cuff portions of the trousers and for holding the cuff portions against slipping on the overlapped portions of the trousers legs at the time pressure is applied thereon, whereby the pressed cuff will be uniform in length and constriction and wrinkling of the trousers legs at and slightly above the upper end of the cuff will be obviated.

A still further object of the invention is to provide a device of the character described which is of simplified construction and is adapted to be applied to a pressing machine of ordinary construction without any extensive changes, if any, being required in the construction of the latter, and with-

out interfering in any way with the operation of the pressing machine in the usual manner.

Other objects and advantages will be apparent from the following description, considered in conjunction with the accompanying drawings, in which

Figure 1 is a top plan view showing the invention applied to a pressing machine, the latter being only partially shown.

Figure 2 is a front view of the structure exhibited in Figure 1, and

Figure 3 is a side elevation of the structure shown in the preceding views, the pressing position of the top leaf of the pressing machine being indicated by the dotted lines and the position of the attachment at that time also being indicated by dotted lines, the raised or inactive positions of the upper pressing leaf and of the attachment being indicated by full lines.

As is well known, the legs of trousers usually taper and decrease in cross sectional area toward their lower ends. In consequence, when the lower end portions of the trousers legs are turned up to provide cuffs, the overlapping upturned portion is of less area at its upper end than at its lower end and therefore tends to constrict the trousers leg at the upper end of the cuff, making the cuff unsightly in appearance and causing wrinkling of the trousers leg for a considerable distance up the trousers leg. This wrinkling of the trousers leg cannot be entirely eliminated by pressing and heretofore, it has been necessary to "take in" the trousers leg at the sides in order to prevent wrinkling and constriction of the trousers leg when the lower end portion thereof is turned up to form a cuff.

When a pressing machine of ordinary construction is equipped with the invention, the lower end portions of the trousers legs can be stretched at the time the trousers legs are pressed so that wrinkling and constriction of the trousers legs at the upper ends of the cuffs are precluded without there being any necessity of making changes in the trousers legs.

The invention comprises a pair of stretching and shaping tongues 1 connected and held in parallel relation by a connecting strip 2. The tongues 1 and the connecting strip 2 preferably are integral portions of a single sheet of any suitable material possessing inherent resiliency, such as spring steel, bronze, brass or other spring metal.

Each of the tongues 1 has a relatively wide end portion 3 which extends approximately one-third of the length of the tongue. Lateral shoulders as at 4 thus are defined at the juncture of the relatively wide end portions 3 of each tongue with the remaining portion of the tongue. The width of the connecting portion 2 preferably is approximately the same as the length of the relatively wide portions 3 and the connecting portion 2 is merged at its ends into the adjacent sides of the relatively wide end portions 3.

The remaining portion of each tongue is uniform in width from its juncture with the relatively wide end portion 3 for approximately half the length of the remaining portion of the tongue, as indicated at 5, and then tapers in width for the remainder of the length thereof, as indicated at 6. With this arrangement, the side edges of the portion 5 of each tongue will be parallel while the side edges of the end portion 6 will converge slightly from the juncture of the portion 6 with the portion 5 toward the adjacent or narrower end of the tongue.

Each tongue is arched or bowed upwardly transversely thereof and is regularly convexo-concave in cross section throughout its length, as best seen in Figure 2. The side edges of the portions 5, 6 of each tongue are beveled or inclined upwardly and outwardly from the lower face of the tongue to the upper face thereof as indicated at 7 for a purpose to be presently described.

A pressing machine of a well known and ordinary type of construction is partially illustrated in the drawing and is designated generally 8. This pressing machine includes a lower leaf or bed 9 upon which the garment which is to be pressed is placed, and an upper or presser leaf 10 which is carried by a lever 11 and is movable to and from position to rest flatwise upon the lower leaf 9 and thus to cooperate with the lower leaf 9 to press a garment that has been placed on the lower leaf. The lever 11 is of the usual forked type and is fulcrumed intermediate its length, as at 11^a, on the axle 11^b of the pressing machine. The axle 11^b is supported by the frame members 11^c. A rock shaft 12 is supported by front extensions 16 on the members 11^c of the frame structure of the pressing machine 8. A tension spring 13 is attached at one end to an upstanding eye 13^a on the rock shaft 12 and is attached at its

other end to an upstanding arm 13^b which is rigid with the lever 11 and is located rearwardly of the axle 11^b.

The unit which comprises the pair of tongues 1 and the connecting strip 2 is disposed between the lower leaf 9 and the upper leaf 10 so that the convexly curved faces of the tongues 1 will be uppermost and the side edges of each of the tongues 1 will be out of contact with the upper face of the lower leaf 9 when the tongue is in raised position as shown in full lines in Figure 3. This unit will be supported between the leaves 9 and 10 of the pressing machine in the position just described through the agency of arms 14 which are rigidly connected at their rearward ends to the rock shaft 12 and are secured adjacent to their front ends to the enlarged end portions 3 of the tongues of the attachment.

From the foregoing description of the various parts of the device, the operation thereof may be readily understood. The lower ends of trousers legs, whether provided with cuffs or not, are slipped over the tapering end portions 6 of the tongues until the shoulders 4 abut the trousers legs at their lower ends. Since the tongues are convexo-concave in cross sectional contour and the horizontal distance between the side edges of the portions 4 of each tongue is less than the width of the lower end portion of a trousers leg, the lower end portion of the trousers leg may be quickly and conveniently placed on the tongue in the position mentioned. When the lever 11 is operated in such manner as to cause movement of the upper leaf 10 downward toward the lower leaf 9, the rock shaft 12 will be permitted to rock in the direction required to cause the unit 1-2-1 to be moved downward also toward the lower leaf 9. The upper leaf 10 will force the unit 1-2-1 downward toward the lower leaf 9 against the action of the spring 13. The side edges of the tongues will be moved into contact with the upper face of the leaf 9 at approximately the same time the upper leaf 10 is moved into contact with the upper faces of the tongues 1. Further downward movement of the upper leaf 10 and continued rocking of the shaft 12 will cause the tongues 1 to be flattened out so that the effective width of the tongues will be increased to an extent sufficient to cause stretching of the overlapping lower end or cuff portions of the trousers legs. This stretching of the lower end portion of the trousers legs will take place coincidently with the pressing of such portions of the trousers legs and as a result, the pressed lower ends or cuff portions of the trousers legs will be uniform in width throughout their length and wrinkling, kinking or constriction of the lower end portions of the 130

trousers legs at the lower ends thereof and particularly at or adjacent to the upper edge of the cuffs thereon will be obviated. Since the side edges of the portions 5, 6 of the 5 tongues are beveled in the manner described, these portions of each tongue will contact at their sides with the portion of a trousers leg thereon along substantially straight single lines so that the lines of contact of each 10 tongue with the trousers portion thereon will coincide with the crease lines resulting from the pressing of the trousers leg.

The laterally expanding tongues will engage with the portions of the trousers legs 15 thereon to prevent slipping or movement of the trousers legs on the lower leaf 9 when pressure is applied on the trousers legs by the upper leaf 10. Therefore, the cuffs of trousers pressed through the use of a 20 pressing machine equipped with the invention will be uniform in length at all points therearound. The cuffs of trousers pressed by means of an ordinary pressing machine without the use of my attachment are likely 25 to have the sides thereof of different lengths since the downwardly moving upper leaf will push the upper side of an upturned overlapping portion of the cuff downward as the upper leaf of the pressing machine 30 moves to pressing position in respect to the lower leaf so that one side of the cuff will be longer than the other side thereof when the pressing has been accomplished.

When the lever 11 has been manipulated 35 to move the upper leaf 10 upwardly out of contact with the attachment, the inherent resiliency of the material of which the tongues 1 are composed will cause the tongues to assume the arched or upwardly 40 bowed shape indicated by the full lines in the drawings and the spring 13 will act to swing the unit 1-2-1 upwardly from the lower pressing leaf. The trousers legs then 45 may be readily removed from position on the tongues.

It will be obvious that an economy in time and labor will be effected when a pressing machine is equipped with my invention since with the use of the attachment, trousers legs can be pressed quickly, satisfactorily and in a uniform manner with but 50 very little skill, if any, being required on the part of the operator.

Obviously, my invention is susceptible of 55 embodiment in forms other than that illustrated in the accompanying drawings and I therefore consider as my own all modifications and adaptations of the form of the device herein described which fairly fall within 60 the scope of the appended claims. For example, the tongues may be apertured as at 15, for the passage of steam should the invention be used with a pressing machine that admits steam between the presser leaves 65 from the bottom.

I claim:—

1. In a pressing machine having a pair of relatively movable cooperative presser leaves, a tongue supported between said presser leaves, said tongue being insertable 75 in the lower end of a trousers leg, said tongue being transversely and resiliently bowed and being adapted to be flattened out by pressure applied thereon by said presser leaves to effect stretching of said overlapping portion of the trousers leg.

2. The combination with a pressing machine having a pair of cooperative relatively movable presser leaves for pressing out an article placed therebetween, a tongue supported between said leaves to move substantially in unison with one of said leaves against the other leaf, said tongue being made of light gauge material possessing inherent resiliency and being substantially ar- 80 cuate in cross sectional contour, said tongue comprising a relatively wide end portion, a second end portion tapering in width toward its outer end and being of less width 85 at its inner end than the first named end portion and an intermediate portion merging said end portions one into the other, the side edges of said intermediate portion being parallel. 90

3. The combination with a pressing machine having a pair of cooperative relatively movable presser leaves for pressing out an article placed therebetween, a tongue supported between said leaves to move substantially in unison with one of said leaves 100 against the other leaf, said tongue being made of light gauge material possessing inherent resiliency and being substantially arcuate in cross sectional contour, said tongue comprising a relatively wide end portion, a second end portion tapering in width toward its outer end and being of less width 105 at its inner end than the first named end portion and an intermediate portion merging said end portions one into the other, the side edges of said intermediate portion being parallel, and being beveled upwardly and outwardly from the lower face of the tongue to the upper face thereof. 110

4. The combination with a pressing machine having a fixed lower leaf, an upper leaf movable to and from position to engage with the lower leaf and to cooperate with the latter to press an article placed therebetween and means for operating the 115 upper leaf, a unit positioned between said leaves adjacent to said lower leaf, and means for attaching said unit to the operating means for said upper leaf to permit said unit and said upper leaf to be moved against said lower leaf at the same time, said unit comprising a pair of parallel tongues having connecting strips merging the tongues one into the other at the inner ends thereof, each of said tongues being made of a ma- 120 125 130

4

terial possessing inherent resiliency and being adapted to have the outer end thereof inserted in the lower end of a trousers leg, each tongue increasing in width from its outer end for a slight distance, then remaining uniform in width for part of its length and finally being enlarged in width at its juncture with said connecting strip, each tongue also being bowed upwardly transversely thereof.

5. In a pressing machine having a pair of relatively movable cooperative presser leaves, a tongue adapted to be supported between said presser leaves, said tongue being insertable in the lower end of a trousers leg, being transversely bowed and adapted to be flattened out by pressure applied thereon by said presser leaves, and being apertured, for the purpose described.
